ABSTRACT OF THE DISCLOSURE

An olefinic gasoline is converted to produce higher octane products by alkylating the C₅ fraction, extracting the C₇ fraction to remove aromatics, dehydrocyclizing the raffinate to produce additional aromatics and cycling at least one material in the C₃ to C₅ range from the dehydrocyclization product to the alkylation step.

In order to reduce undesirable emissions from internal combustion engines used in automobiles to a minimum in some instances it is desirable to utilize catalytic converters associated with the exhaust system to treat the exhaust gases prior to venting to the atmosphere. When using such a catalyst it is often desirable to remove completely or to reduce the amount of tetraethyl lead used in the gasoline. Therefore, in such instances, it becomes important to produce gasolines having as high an octane number as possible without lead addition. The present invention is directed toward upgrading olefin-containing gasoline by conversions to produce higher octane components.

According to the invention a gasoline feed is upgraded by separating it to produce a C₅ stream, a C₆ stream and a C₇ stream, alkylating the C₅ stream with isobutane, dehydrogenating the remaining pentanes, feeding a dehydrogenated product to the alkylation step, solvent extracting the C₇ stream to recover aromatics, dehydrocyclizing the raffinate stream to produce additional aromatics and feeding at least one component of the dehydrocyclization in the range of C₃ to C₅ to the alkylation step.

In the drawing, FIG. 1 and FIG. 2 are diagrammatic flow sheets of two embodiments of the invention.

In the embodiment of FIG. 1 an olefin-containing gasoline line stream is fed through pipe 11 to separation zone 12. A C₅ fraction is removed through pipe 13, a C₆ fraction through pipe 14 and a C₇ fraction through pipe 16. The C₅ fraction is fed to alkylation zone 17 along with isobutane from pipe 18. The alkylated product is passed through pipe 19 to separation zone 21. The alkylate is removed through pipe 22, isobutane is recycled through pipe 23 and pipe 24 to alkylation zone 17. Propane and butanes are removed through pipe 25. The C₅ fraction is fed through pipe 26 to dehydrogenation zone 27. The product of the dehydrogenation step is fed through pipe 28 to separation zone 29.

The C₇ fraction from pipe 16 is solvent extracted in solvent extraction zone 31 and the aromatic extract fraction is recovered through pipe 42. The raffinate is fed through pipe 33 to dehydrocyclization zone 34 and the product, containing additional aromatics, is fed through pipe 36 to separation zone 37. A fraction comprising benzene, toluene and C₇⁺ is passed through pipe 38 and returned to solvent extraction zone 31 while the remaining lighter fractions are passed through pipe 39 to separation zone 29. From separation zone 29 a light fraction comprising hydrogen, carbon dioxide and C₁—C₂ hydrocarbons is removed through pipe 41. A C₃—C₅ fraction is returned through pipe 42 and pipe 24 to alkylation zone 17 while the C₆ fraction is removed through pipe 43 and can be combined with the C₆ fraction in pipe 14.

In FIG. 2 a gasoline fraction is fed through pipe 44 to separation zone 46. A fraction comprising C₅ hy-

2

drocarbon is removed through pipe 47, a fraction comprising C₆ hydrocarbons through pipe 48, a fraction comprising C₇ hydrocarbons through pipe 49 and a heavier fraction through pipe 51. The C₅ fraction is fed to alkylation zone 52 through pipe 53 along with isobutane from pipe 54. The alkylated product is passed through pipe 56 to separation zone 57. The alkylate is removed through pipe 58, propane and butanes removed through pipe 59, isobutane recycled through pipe 60, and C₅'s passed to dehydrogenation zone 61 through pipe 62. The product of the dehydrogenation step is fed through pipe 63 to separation zone 64.

The C₇ fraction from pipe 49 is solvent extracted in solvent extraction zone 66 and the aromatic fraction is recovered through pipe 67. The raffinate is fed through pipe 68 to dehydrocyclization zone 69 and the product, containing additional aromatics, is fed through pipe 71 to separation zone 64. From separation zone 64 a light fraction comprising any hydrogen, carbon dioxide and C₁ and C₂ hydrocarbons is removed through pipe 72. The remainder of the products from separation zone 64 are recycled through pipe 73 to separation zone 46.

The aromatic extraction zone of the process of the present invention can comprise any conventional method for separating aromatics from other hydrocarbons. One example is a solvent extraction unit (Undex Unit) which use, as a solvent, an alkylene glycol, preferably diethylene glycol or a diethylene glycol-triethylene glycol-water mixture. Such a solvent extraction unit can comprise a multi-stage counter current extraction column associated with appropriate stripper columns, recirculation means, decantation means, washing means, and the like. A highly aromatic stream is discharged from this zone as well as a stream containing C₇⁺ olefins and paraffins.

In the pentane dehydrogenation zone, the pentanes are contacted under reaction conditions with any suitable catalyst which has activity for dehydrogenation of paraffins to form monoolefins. A number of such catalysts is known. One suitable class of such dehydrogenation catalysts comprises a steam-stable Group II metal aluminate impregnated with a Group VIII metal and a tin-group metal. Particularly preferred are compositions containing zinc aluminate, tin, and platinum. A particularly effective catalyst is a zinc aluminate (containing a slight excess of zinc) which has been impregnated with 0.4–0.6 weight percent platinum, and 0.4–1 weight percent tin.

The pentane dehydrogenation catalysts operate at 750–1250° F., preferably 1000–1100° F.; at 0–500 p.s.i.g., preferably 50–300 p.s.i.g.; at a steam:hydrocarbon mole ratio of 0.5–30, preferably 3–20; and at a hydrocarbon space rate of 0.1–10, preferably 0.5–5 LHSV.

In the catalytic dehydrocyclization zone of the process, the C₇⁺ hydrocarbons are contacted, under reaction conditions, with any suitable catalyst which has substantial dehydrocyclization (aromatization) activity. For example, a suitable catalyst is a platinum-containing catalyst prepared by depositing platinum on a cracking catalyst such as silica-alumina. Another suitable catalyst is alumina containing combined halogen such as fluorine. Other catalysts which may be utilized in this zone include Group VIII metals deposited on other supports such as alumina, magnesia, thoria, zirconia, and the like. However, the particularly preferred dehydrocyclization catalyst is the dehydrogenation catalyst comprising a Group VIII metal-promoted Group II metal aluminate described above for use in the pentane dehydrogenation zone. That catalyst, when contacted with C₇⁺ hydrocarbons, produces substantial amounts of aromatic products with high selectivity. The conditions for the dehydrocyclization zone are essentially identical with the conditions described above for the pentane dehydrogenation zone.

The alkylation zone can employ any suitable alkylation catalyst using any known alkylation conditions to provide a high octane alkylate. A suitable catalyst is hydrofluoric acid at a temperature of 50-100° F., a contact time of 1-10 minutes, and a suitably high isobutane ratio (for example, 6-15 moles isobutane per mole of olefin).

Other than the aromatic extraction zone previously described, the separation zones in the process of the invention can comprise any suitable means, such as fractional distillation, to achieve the separations indicated. The separation of the hydrocarbon mixtures shown is within the skill of the art.

In a calculated example, according to the invention as illustrated in FIG. 2, a catalytic cracked gasoline is fed through pipe 44. A pentenes and lighter fraction is fed through pipe 47, a stream comprising a 120-185° F. boiling fraction through pipe 48 and a 185-300° F. boiling fraction through pipe 49. The 300° boiling plus fraction is taken through pipe 51.

Alkylation zone 52 is an HF alkylation zone operated at a temperature of about 90° F., sufficient pressure to maintain liquid phase with a HF/hydrocarbon volume ratio of 4:1, an isobutane/olefin mole ratio of 12:1 and with an average contact time of about 1 minute. Solvent extraction zone 66 is a diethylene glycol extraction step operated at a temperature of about 100° F., a pressure of 150 p.s.i.g. and with a solvent/hydrocarbon liquid/liquid volume ratio of about 4:1. Dehydrogenation zone 61 presents a dehydrogenation step utilizing a platinum/tin/zinc aluminate catalyst at a temperature of 1050° F., a pressure of 100 p.s.i.g., a ratio of moles of steam to moles of hydrocarbon of about 7 and with a gaseous weight hourly space velocity of about 1000. Dehydrocyclization zone 69 represents a step utilizing a platinum/tin/zinc aluminate catalyst at about 1050° F., 100 p.s.i.g. a ratio of moles of steam to moles of hydrocarbon of about 7 and a liquid hourly space velocity of about 1.5.

The results are shown in the following table. The improvement in octane number is clearly demonstrated.

5

What is claimed is:

1. A process for upgrading a gasoline feed comprising the steps of:

separating said gasoline feed to produce a first separated stream comprising a major portion of the C₅ content of said gasoline feed, a second separated stream comprising a major portion of the C₆ content of said gasoline feed, and a third separated stream comprising a major portion of the C₇ content of said gasoline feed; alkyllating said first separated stream with isobutane; separating the product stream from said alkyllating step to produce an alkylated product stream and a fourth separated stream comprising pentanes; dehydrogenating said fourth separated stream to produce a dehydrogenation product stream; feeding at least one component of said dehydrogenation product stream in the range of C₃ to C₅ to said alkyllating step; solvent extracting said third separated stream to produce an extract stream containing aromatic compounds and a raffinate stream; dehydrocyclizing said raffinate stream to produce a dehydrocyclization product stream; feeding at least one component of said dehydrocyclization stream in the range of C₃ to C₅ to said alkyllating step; and recycling a C₇ component of said dehydrocyclization stream to said dehydrocyclization step.

2. A process according to claim 1 wherein said gasoline feed is separated in a first separation zone; said product stream from said alkyllating step is separated in a second separation zone; isobutane is recycled from said second separation zone to said alkyllating zone; said dehydrogenation product stream is separated in a third separation zone; said dehydrocyclization product stream is separated in a fourth separation zone; a stream comprising benzene, toluene and C₇⁺ hydro-

* MSCF: b Aromatic free.   ° Benzene, toluene, xylene plus C₆.

- carbons is returned from said fourth separation zone to said solvent extraction zone;
- a stream comprising the remaining lighter fractions is passed from said fourth separation zone to said third separation zone; and
- a C₃-C₅ fraction is returned from said third separation zone to said alkylation zone.
3. A process according to claim 1 wherein:
- said gasoline feed is separated in a first separation zone; the product stream from said alkylation step is separated in a second separation zone;
- separate streams one comprising propane and butanes and the other comprising alkylate are removed from said second separation zone;
- isobutane is recycled from said second separation zone to said alkylation zone;
- said dehydrogenation product stream and said dehydrogenation product stream are both fed to a third separation zone; and

said at least one component of said dehydrocyclization stream in the range of C₃ to C₅ is fed to said alkylation step by passage from said third separation zone to said first separation zone.
